(57) **CLAIM**

The ornamental design for a nursing bottle, as shown and described.

DESCRIPTION

FIG. 1 is an isometric view of an embodiment of a nursing bottle showing the new design with the nipple portion shown by broken lines, the nipple portion being shown as environmental only and not forming a part of the design;

FIG. 2 is a front view of the nursing bottle shown in FIG. 1 with the nipple portion shown by broken lines, the nipple portion being shown as environmental only and not forming a part of the design;

FIG. 3 is a rear view of the nursing bottle shown in FIG. 1 with the nipple portion shown by broken lines, the nipple portion being shown as environmental only and not forming a part of the design;

FIG. 4 is a top plan view of the nursing bottle shown in FIG. 1 with the nipple portion shown by broken lines, the nipple portion being shown as environmental only and not forming a part of the design;

FIG. 5 is a bottom plan view of the nursing bottle shown in FIG. 1;

FIG. 6 is an isometric view of the nursing bottle shown in FIGS. 1-5 with a cap thereon; and,

FIG. 7 is a front view of the nursing bottle shown in FIG. 6, the rear view being identical.

1 Claim, 5 Drawing Sheets
